Fig. 3

Fig. 4

Fig. 5

Fig. 6

FIG. 1 is a perspective view of the X-ray diffractometer showing our new design;

FIG. 2 is a front elevational view of the X-ray diffractometer housing of FIG. 1;

FIG. 3 is a top plan view of the X-ray diffractometer housing of FIG. 1;

FIG. 4 is a left-hand side elevational view of the X-ray diffractometer housing of FIG. 1;

FIG. 5 is a right-hand side elevational view of the X-ray diffractometer housing of FIG. 1; and

FIG. 6 is a rear elevational view of the X-ray diffractometer housing of FIG. 1.

We claim:

The ornamental design for an X-ray diffractometer housing, as shown and described.
